UNITED STATES PATENT OFFICE.

FREDERICK WILLIAM MARHEINE, OF SPOKANE, WASHINGTON, ASSIGNOR OF ONE-HALF TO EMIL HANSEN, OF SPOKANE, WASHINGTON.

SASH-HOLDER.

1,381,725.

Specification of Letters Patent. Patented June 14, 1921.

Application filed May 20, 1918. Serial No. 235,520.

To all whom it may concern:

Be it known that I, FREDERICK WILLIAM MARHEINE, a citizen of the United States, residing at Spokane, in the county of Spokane and State of Washington, have invented new and useful Improvements in Sash-Holders, of which the following is a specification.

This invention relates to new and useful 10 improvements in sash holders and the principal object of the invention is to provide a simple device for holding the sash in a number of different positions and for locking the sash in closed position.

15 Another object of the invention is to provide a device of this character which is simple and durable in construction, reliable and efficient in operation and one which can be manufactured and placed upon the market at a minimum cost.

20 The invention also consists in certain other features of construction and in the combination and arrangement of the several parts, to be hereinafter fully described, illustrated 25 in the accompanying drawings and specifically pointed out in the appended claim.

In describing my invention in detail, reference will be had to the accompanying drawings wherein like characters denote like 30 or corresponding parts throughout the several views, and in which:—

Figure 1 is an elevation showing the sash locked in closed position.

Fig. 2 shows the sash in partly raised position.

Fig. 3 shows the device used to lock the top sash.

As will be seen from the drawings the invention includes a pair of members 1 and 40 2, one adapted to be secured to the sash and the other to the window frame. The member 1 is of L-shape and is provided with a hole at the corner thereof which is adapted to receive a screw or the like by which the 45 member is pivoted to the frame. The member 2 is also of substantially L-shape but the

short part 2' is slightly inclined in relation to the part 2". This part 2 is secured to the sash in such a manner that the part 2' is held in an inclined position with respect 50 to the sash. In this way when the window is closed the end of the member 1 will engage with this inclined part, and as the member 1 is in inclined position the sash will be held in closed position as, when an attempt is made to raise the sash the end of 55 member 1 will engage and be clamped by the vertical part 2" and thus lock the parts against movement. The window may be unlocked by simply pressing up on the long 60 arm 1' of the member 1.

In Fig. 2 the window is shown in partly raised position with the arm 1' engaging the tip of the part 2.

It will be seen that the lock will automatically lock the sash as soon as the sash is lowered and it will also hold the sash in a number of different positions. With this invention it is unnecessary to use the 65 weights and ropes now in use.

70 It is thought from the foregoing description that the advantages and novel features of my invention will be readily apparent.

I desire it to be understood that I may make such changes in the construction and 75 in the combination and arrangement of the several parts, provided that such changes fall within the scope of the appended claim.

What I claim is:—

In combination with a window frame and 80 its sash, of locking means for the sash consisting of an L-shaped member pivoted on one part at the junction of its arms and a stationary member on the other part, said L-shaped member having a short arm and 85 a long arm and the stationary member having a straight vertical part and an inclined part, said inclined part receiving the end of the short arm with the corner of said arm resting against the vertical part.

90 In testimony whereof I affix my signature.

FREDERICK WILLIAM MARHEINE.
